United States Patent Office.

E. C. HENDERSON AND R. A. HENDERSON, OF ALBIA, IOWA.

Letters Patent No. 80,954, dated August 11, 1868.

IMPROVED MILLSTONE-MACHINE.

The Schedule referred to in these Letters Patent and making part of the same.

TO ALL WHOM IT MAY CONCERN:

Be it known that we, E. C. HENDERSON and R. A. HENDERSON, of Albia, in the county of Monroe, and State of Iowa, have invented a new and improved Millstone-Dressing Machine; and we do hereby declare that the following is a full, clear, and exact description thereof, which will enable those skilled in the art to make and use the same, reference being had to the accompanying drawings, forming part of this specification, in which—

Figure 1 is a sectional elevation of our invention, the section being taken through the line $z z$ of fig. 2.

Figure 2 is a top view of the machine.

Figure 3 is a detail end view of the lever-head and picking-plates.

Similar letters of reference indicate corresponding parts.

The object of this invention is to provide a simple and effective machine for dressing millstones in a uniform and expeditious manner, whereby the operation of cutting the furrows in the stone can be performed by a person not necessarily skilled in using the hand-pick for the same purpose.

It consists of a pick, operated by a train of mechanism, the motion of which is produced by simply turning a hand-crank.

In the accompanying drawings—

A is the general frame of the machine.

B are bearing-blocks, which afford bearings for the shafts C D of the mechanism operating the pick-lever E.

These blocks slide to and fro in grooves, a , in the frame of the machine, and are held within said grooves by the strap-plates G, one of which is broken away in fig. 2, to exhibit the bearing-block B beneath it.

When the crank H is turned, the blocks B, and the entire pick-mechanism which they support, are moved forward or backward by means of the pinions I on the shaft C, which pinions engage with the racks J, affixed in suitable positions to the frame A, as shown.

Motion is communicated to the shaft D from the shaft C, by means of engaging cog-wheels K and L, keyed on their respective shafts, as shown, the wheel L being a relatively small wheel or pinion, so that the shaft D will be revolved much faster than the shaft C, for the purpose of actuating the pick-lever E to vibrate rapidly, as it progresses, horizontally, and thus strike the picking-plates M upon the stone in a close succession of places.

The vibration of the lever is accomplished by a cam or eccentric, O, keyed on the shaft D, the said eccentric revolving within an elongated eye, P, forming part of the lever, which, as one end of the said lever is pivoted on the shaft C as a centre, causes the picking-plates M held in the lever-head Q to impinge upon the face of the stone in a rapid and regular manner.

In operation, the machine is laid upon the face of the stone in the proper direction for cutting the required furrow.

The crank-handle is then turned alternately in reverse directions, which operation moves the lever back and forth in the same line, and at the same time causes it to vibrate, thus inflicting a series of blows with the picking-plates, whereby the face of the stone is dressed in the manner required.

The head Q is formed with a deep rectangular clove or slot, and provided with set-screws, b, for holding any required number of picking-plates, so that furrows of different widths may be cut by the same machine, when desired.

This form of the head is shown at fig. 3.

We claim as new, and desire to secure by Letters Patent—

1. The sliding bearing-blocks B, operated by means of the rack and pinion I J, for giving to the pick of a millstone-dressing machine a horizontal motion, substantially as shown and described.
2. The shafts C D, connected by gearing K L, and provided with the pinions I and eccentric, O, when said

shafts have their bearings in the sliding blocks B, and are arranged, with relation to the rack J and frame A, substantially as herein described.

3. The pick-lever E, when fitted at one end to turn upon the shaft C, and formed with an elongated eye, P, adapted to receive the eccentric, O, on shaft D, said lever being arranged to be operated both vertically and horizontally within the frame A, in the manner and by the means herein shown and described.

E. C. HENDERSON,
R. A. HENDERSON.
